UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

PROCESS OF WIRE-TYING AND PACKAGING BAGS.

1,170,037.

Specification of Letters Patent.

Patented Feb. 1, 1916.

Application filed September 8, 1913. Serial No. 788,516.

To all whom it may concern:

Be it known that I, ADELMER M. BATES, a citizen of the United States, residing at Chicago, in the county of Cook and State of Illinois, have invented a certain new and useful Improvement in Processes of Wire-Tying and Packaging Bags, of which the following is a specification.

My invention relates to a method or process of wire tying and assembling bags for packaging them.

The process is illustrated roughly in the accompanying diagrammatic sketch, wherein—

15 Figure 1 is a view of two sections of wire. Fig. 2 a view of the same, with one end of each twisted together. Fig. 3 a view of the same with the twisted ends inwardly turned. Fig. 4 a view of the parts as arranged in 20 Fig. 3, with the gathered end of the bag in position. Fig. 5 is a view of the parts after the tie has been tightened. Fig. 6 is a view of the end of the wires after the tie has been severed. Fig. 7 is a side view of the 25 tie in position on the bag after it has been severed from the wires. Fig. 8 is a view of a series of bags, illustrating the manner in which the loop key is forced into position when the bags are arranged so as to be gathered in packages.

30 Like parts are indicated by the same letters.

The drawings are roughly diagrammatic and intended to be suggestive rather than descriptive of the several steps in the process.

A and B are the ends of two wires. They may each be derived from a coil. C represents the two ends of such wires twisted 40 together and C¹ indicates such twisted ends forced inwardly.

D are the gathered ends of the bags E.

F is a portion of the two wires at the point where they are twisted together.

45 G is the key loop.

G¹ are the twisted ends of the wires after they are severed, projecting from and associated with the key loop G. G² shows these 50 twisted ends turned in toward the center of the key loop.

J is a platform or chute of any kind or description.

K are bars supporting, in any desired manner and of any desired shape, but so as

to engage the gathered ends of the bags and 55 hold them.

M illustrates the key loop and its associated parts bent into parallelism with and among the folds of the gathered bag end by contact with the next succeeding bag.

60 In wire-tying bags, it is highly important that there be no scraps or pieces of wire or loops of wire about the premises. They are troublesome, expensive to handle and injurious in many ways. Their use entails 65 a considerable loss of wire and if loops are formed, their manufacture and use involves another operation or series of operations.

70 My process therefore begins with the use of two coils of wire and I make a series of bag ties from their two ends. The free ends of the wires are first in some manner twisted as indicated in Figs. 2 and 6, and they are then turned inwardly toward, but preferably not parallel with the strands of wire, 75 and they may be brought into the position indicated by dotted lines in Fig. 7. The two wires are held so as to be taut and the gathered end of the bag is then brought in between the two wires and forced into the position indicated in Fig. 4. A proper manipulation of the parts will bring the twisted end in between the folds, or if desired, it may be made to penetrate the fabric of the bag so these parts will be in the position indicated in Figs. 4 and 7. The two strands 80 of wire beyond but near the bag are now twisted preferably so as to form a key loop, as indicated in Fig. 5, and the twisting process is continued until the tie is sufficiently tightened about the bag end and if 85 a key loop has been formed, the parts will assume the position shown in Fig. 5. The wires are then severed somewhere along the twisted portion between the strands and the key loop, as indicated with a dotted line in 90 Fig. 5. This leaves the severed parts in the relation indicated respectively in Figs. 6 and 7, but the part C of Fig. 6 must now be bent into the position indicated by C¹ in 100 Fig. 3. The projecting end or key loop of the tie may now be forced up into or parallel with the folds of the gathered end of the bag in any desired manner, but this may 105 preferably be done in connection with packaging the bags, or the bags may be arranged between guide bars, held together in any suitable manner, as indicated in Fig. 8, and

- as each bag is forced into position, it thrusts the projecting end or key loop of the next adjacent bag up into parallelism with the folds. By sliding the bags along as from time to time each is properly tied, they will fall out somewhat as roughly indicated in Fig. 8 at the end, whereupon they can be gathered for packaging. By working this process, and it may be done by hand or any desired mechanism, the first formed twisted end penetrates between the folds or into the fabric of the bag, so that it cannot injure objects coming in contact with the end of the bag, it cannot be untwisted, and it prevents the tie from being slipped off the end of the bag. Such a process for tying a bag results also in furnishing a key loop with a protected end, because the end is within the loop and parallel with the wire which forms the loop. The key loop itself is entirely out of a position where it may come in contact with other objects, because it lies up around and more or less buried among the folds of the bag.
- 25 The several steps of manipulation may of course be varied without departing from the spirit of my invention, and the particular form and shape of the tie is not essential.
- I claim:
- 30 1. A method of wire-tying bags, which consists of twisting together the ends of two strands of wire, bending the twisted ends inwardly toward the loop formed by encircling the gathered end of the bag between the wires, with the twisted end in the midst of the fold, twisting the two strands about the bag so as tightly to tie it, and severing the two strands from the tie.
- 35 2. A method of wire-tying bags, which consists of twisting together the ends of two strands of wire, bending the twisted ends inwardly toward the loop formed by encircling the gathered end of the bag between the wires with the twisted end in the midst of the fold, twisting the two strands about the bag so as tightly to tie it, and severing the two strands from the tie in the midst of the twisted portion.
- 40 3. A method of wire-tying bags, which consists of twisting together the ends of two strands of wire, bending the twisted ends inwardly toward the loop formed by encircling the gathered end of the bag between the wires, with the twisted end in the midst of the fold, twisting the two strands about the bag so as to tightly tie it, and severing the two strands from the tie, the two strands twisted so as to form a key loop with a twisted section on each side of the loop.
- 45 4. A method of wire-tying bags, which consists of twisting together the ends of two strands of wire, bending the twisted ends inwardly toward the loop formed by encircling the gathered end of the bag between the wires, with the twisted end in the midst of the fold, twisting the two strands about the bag so as to tightly tie it, and severing the two strands from the tie.
- 50 5. A method of wire-tying bags, which consists of twisting together the ends of two strands of wire, encircling the gathered end of the bag between the wires, twisting the two strands about the bag so as tightly to tie it, and severing the two strands from the tie, bending the twisted end of the wires between the folds, with the twisted end in the midst of the fold, twisting the two strands about the bag so as to tightly tie it, and severing the two strands from the tie.
- 55 6. A method of wire-tying bags, which consists of twisting together the ends of two strands of wire, encircling the gathered end of the bag between the wires, twisting the two strands about the bag so as tightly to tie it, and severing the two strands from the tie, bending the twisted end of the wires between the folds, with the twisted end in the midst of the fold, the two strands twisted so as to form a key loop with a twisted section on each side of the loop and severing the two strands in the midst of the outer twist, and bending the projecting portion of the tie into parallelism with and among the folds of the gathered end of the bag.
- 60 7. A method of wire-tying bags, which consists of twisting together the ends of two strands of wire, encircling the gathered end of the bag between the wires, with the twisted end in the midst of the fold, twisting the two strands about the bag so as to tightly tie it, and severing the two strands from the tie, and bending the projecting portion of the tie into parallelism with and among the folds of the gathered end of the bag.
- 65 8. A method of wire-tying bags, which consists of twisting together the ends of two strands of wire, encircling the gathered end of the bag between the wires, twisting the two strands about the bag so as to tightly tie it, and severing the two strands from the tie in the midst of the twisted portion, and bending the projecting portion of the tie into parallelism with and among the folds of the gathered end of the bag.
- 70 9. A method of wire-tying bags, which consists of twisting together the ends of two strands of wire, bending the twisted ends inwardly toward the loop to be formed by encircling the gathered end of the bag between the wires with the twisted end in the midst of the fold, twisting the two strands about the bag so as to tightly tie it, and severing the two strands from the tie in the

midst of the twisted portion, and bending the projecting portion of the tie into parallelism with and among the folds of the gathered end of the bag.

- 5 10. A method of wire-tying bags, which consists of twisting together the ends of two strands of wire, encircling the gathered end of the bag between the wires, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

- 10 15. A method of wire-tying bags, which consists of twisting together the ends of two strands of wire, bending the twisted ends inwardly toward the loop to be formed by encircling the gathered end of the bag between the wires, with the twisted end in the midst of the folds, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

- 20 25. A method of wire-tying bags, which consists of twisting together the ends of two strands of wire, encircling the gathered end of the bag between the wires, with the twisted end in the midst of the folds, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

- 30 35. A method of wire-tying bags, which consists of twisting together the ends of two strands of wire, encircling the gathered end of the bag between the wires, with the twisted end in the midst of the folds, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

40 45. A method of wire-tying bags, which consists of twisting together the ends of two strands of wire, bending the twisted ends inwardly toward the loop formed by encircling the gathered end of the bag between the wires, with the twisted end in the midst of the folds, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

50 55. A method of wire-tying bags, which consists of twisting together the ends of two strands of wire, bending the twisted ends inwardly toward the loop formed by encircling the gathered end of the bag between the wires, with the twisted end in the midst of the folds, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

60 65. A method of wire-tying bags, which consists of twisting together the ends of two strands of wire, bending the twisted ends inwardly toward the loop formed by encircling the gathered end of the bag between the wires, with the twisted end in the midst of the folds, twisting the two strands about the bag so as to tightly tie it, and severing the two strands from the tie, the two strands twisted so as to form a key loop with a twisted section on each side of the loop, and bending the projecting portion of the tie into parallelism with and among the folds of the gathered end of the bag.

In testimony whereof, I affix my signature in the presence of two witnesses this 3rd day of September 1913.
